UNITED STATES PATENT OFFICE

ALEXANDER GRANT MCGREGOR, OF LONDON, ENGLAND

APPARATUS FOR THE SMELTING OF COPPER ORES AND THE LIKE

Original application filed January 30, 1930, Serial No. 336,288, and in Belgian Congo, December 7, 1928.
Divided and this application filed July 25, 1930. Serial No. 470,707.

This invention relates to apparatus for the smelting of copper ores and the like. Improved methods and processes for the smelting of ores are described and claimed in my concurrent application Serial No. 336,288, filed 30th January, 1930, from which application the present invention is divided. The present invention is hereinafter specifically described with reference to the smelting of copper sulphide ores.

14 copper sulphide ores.
15 It is an object of this invention to provide simplified apparatus in which heat is conserved, the fuel required for smelting is very materially reduced, dusting losses are minimized, and the handling of the products in a heated condition is avoided, and the use of such apparatus will result in increased recoveries as well as less expensive plant, maintenance and labour costs.

20. maintenance and labour costs.

The usual procedure of copper smelting consists broadly in roasting or calcining the ore in roaster furnaces, thereafter producing matte in reverberatory or like furnaces, and then in a separate operation bessemerizing the matte to blister copper in converters.

25. These operations require special plant for handling the ore between the various operations, and as the ore after roasting is hot, dry and dusty, much heat and dust are lost in the transfer between the roasters and the reverberatory furnaces. In the transfer of the matte from the reverberatory furnaces to the converters, and in the transfer of the converter slag from the converters to the reverberatory furnaces, heat is lost, labour and machinery are required, and the skulls which form in the transfer launders and ladles must be gathered and broken up and re-smelted.

30. According to the present invention, the

According to the present invention, the smelting is carried out in a reverberatory furnace-chamber having a length considerably in excess of its breadth or height and mounted to tilt about a longitudinal axis, the chamber being provided with an axial furnace outlet for gases connected to air-preheating apparatus or waste heat boilers through an axial gland, whereby tilting of the furnace is permitted without diluting the outgoing gases with the atmospheric air. Tuyères are provided in the furnace near the bottom thereof.

supplied from a longitudinally-extending air blast pipe and fuel burners are provided in the end opposite from the outlet for gases.

The furnace-gases, after cooling, may be treated for the recovery of sulphur dioxide, and owing to the fact that they are not diluted with excess of atmospheric air such recovery is simplified. 55

Further features of the invention will appear from the following description of certain specific forms of the apparatus, which are given by way of example only, and with reference to the accompanying drawings, in which—

Figure 1 is mainly a longitudinal sectional elevation of one form of the apparatus in accordance with the invention; 65

Figure 2 is a plan partly in section of the same;

same;
Figures 3, 4 and 5 are cross-sections 79. through the furnace, showing it tilted to various positions;

Figures 6 and 7 are details of ore-charging apparatus.

Figure 8 shows a waste heat boiler; 75
Figure 9 is a longitudinal section, and

modified construction;

Figure 11 is a cross-section of the same, and Figure 12 is a longitudinal section of a 80

Figure 12 is a longitudinal view of a further modified construction. The figure shows a base plate with a central opening. A vertical support is positioned in the center of the opening. A horizontal beam extends from the side of the support. The figure is annotated with Roman numerals I, II, III, IV, V, VI, VII, and VIII, which indicate specific parts of the construction.

Like reference numerals indicate like parts throughout the several views.

Referring to the construction illustrated in Figures 1 to 8, a reverberatory furnace 85

in Figures 1 to 8, a reverser assembly, in which chamber 20 is provided, the length of which is greater than its breadth, or

considerably greater than its breadth or height, and which is of the cross-section illustrated in Figures 3, 4 and 5. This is mounted on the framework 21 having curved bearers 22 beneath the furnace which rest on rollers 23 supported by curved base-plates 24. This provides a tilting mounting for the furnace. Gearing 25, which meshes with curved racks 26, is provided for effecting the tilting movements. 95

The furnace is built up of highly refractory material. Along one side of the furnace extends an air blast or bustle pipe 30, having branches 31 to tuyères 32 located in the side 100

of the furnace near the bottom thereof. Above and below the tuyères 32 there may be located in the wall of the furnace water-cooling plates 33 with the necessary water-connections (not shown) where water-cooling is desirable. On the opposite side of the furnace from the tuyères are a number of charging doors 34, and near one end there is a slag-discharge-spout 35. On the charging side of the furnace is a framework 40 supporting a track 41 for charging-cars 42. The cars carry ore-hoppers 43 and charging devices to deliver ore through the doors 34 into the furnace. The charging devices are hereinafter more fully described. Below the platform 40 is a second track 44 on which run slag-cars 45 to receive slag discharged from the spout 35. At the back of the furnace is a third track 46 on which run cars 47 supporting pots 48 to receive molten copper. The molten copper is tapped from the furnace through a discharge-opening, which is not shown in the drawings.

Referring to Figures 4 to 7, the charging devices for the furnace comprise a belt 50 supported on rollers 51 which are carried on a charging frame 52. The frame 52 is mounted on wheels 53 (Figures 4 and 5) so that it can be advanced towards, and retracted from, the furnace. The wheels 53 run on a carrier 54, which is pivoted on the car 42. The belt 50 is driven at a high speed by an electric-motor mounted on the frame 52 but not shown in the drawings. The hopper 43 has a discharge regulating device 55 for delivering ore on to the belt 50. Below the belt 50 a sliding bracket 60 is mounted on the frame 52 and carries a pan 61, which can be advanced, when desired, into the charging door of the furnace. The pan 61 has a spout 62 on its front side and a nozzle 63 supplied by an air-pipe 64 upon the back. The nozzle 63 serves to direct a jet of air under pressure into the pan and out through the spout 62.

The operation of the charging device is as follows:—

Ore delivered on to the belt 50 from the hopper 43 is projected therefrom, either directly into the furnace, or, if desired, into the pan 61.

If the ore is projected directly into the furnace, the belt 50 may be run at a sufficient speed to spread the ore across the whole width of the furnace. If the ore or other material of the charge is delivered into the pan 61 the pressure jet from the nozzle 63 serves to deliver it into the furnace through the spout 62. The pan 61 is pivotally mounted at 64 and can be swung through an angle indicated by the chain-lines in Figure 7 so as to distribute the material uniformly over a large area of the surface of the charge within the furnace.

Reverting to Figures 1 and 2, the furnace-chamber 20 is provided with an axial outlet

70 connected through a coaxial gland 71 with a flue 72. The flue 72 branches into two lateral flues 73, 74, provided with water-cooled dampers 75, 76. In these flues are located waste-heat boilers 77, 78 for the purpose of cooling the molten particles held in suspension by the furnace gases, this cooling being sufficient only to prevent accretions and crusts adhering to the sides of the subsequent flues and brickwork, and the gases, 75 after passing through the waste-heat boilers, are led through suitable reversing valves to regenerators 80, 81. The air blast or bustle-pipe 30, which tilts with the furnace, is led over the end of the flue 72 to a coaxial gland 80 82 by which it is connected to a branched pipe 83, which is connected to the regenerators 80, 81. The connections to the regenerators are as follows:—The flues 73, 74 from the furnace are connected to a cross-flue 90, and the cross-flue 90 is connected by two water-cooled valves 91, 92 to the regenerator 81. It is connected through two other water-cooled valves 93, 94 to the regenerator 80. By operating these valves the cross-flue 90 may be connected to either of the regenerators as desired. The branched pipe 83 is connected by a valve 94' to the regenerator 80, and by a valve 95 to the regenerator 81.

Thus, it will be seen that hot gases coming 95 from the furnace-chamber 20 pass by way of the flues 73, 74 through the waste-heat boilers 77, 78 to the cross-header 90, and thence to one of the regenerator-chambers 80. Meanwhile, air can be drawn in through the other 100 regenerator by way of the branched pipe 83, to the bustle-pipe 30. The connections are reversed by operating the valves 91 to 95, and when this is done, the flow of gases through the waste-heat boilers 77, 78 can be 105 maintained in the same proportions as before by suitably adjusting the dampers 75, 76.

Openings 100 are provided in the other end of the furnace-chamber 20 for liquid or powdered-fuel burners, which are not shown in 110 the drawings. The fuel-burners can be provided either with a separate air supply or with a connection to the hot blast in the bustle-pipe 30.

The regenerators 80, 81 are similar to the 115 hot heat stoves in iron blast furnace practice, wherein the chamber is filled with chequered brickwork, illustrated diagrammatically in the drawings at 110. The regenerators are provided with an outer brick-lined casing 120 111 and hot gases from the chequered brick-work chamber pass through the space provided between the chequered brickwork chamber and the brick-lined casing 111 to an outlet-flue 112. The outlet-flue 112 may be either a 125 forced draught outlet having an injector-nozzle 113, if desired, as shown in the drawings, or it may be connected to a stack for natural draught. A damper 114 controls the outlet and there is an air-inlet 115. When 130

the regenerator is in use for heating air for the bustle-pipe 30, the damper 114 is closed, air is blown in through the pipe 115, passes through the outer space within the brick-lined casing 111, and thence through the 5 chequered brickwork chamber to the valves and bustle-pipe already described.

The operation of the process in the above apparatus is as follows:—It is assumed that the sulphur content of the entire charge to 10 be smelted will be 20 per cent. or more. The furnace is of large size and may be fifty to sixty feet long, or even larger.

Taking as starting point the beginning of 15 a fresh cycle of operations after most of a previously smelted charge of molten copper has been removed from the furnace, the operations will be so arranged that part of the slag and copper from the immediately preceding operation of blowing to blister copper will remain. This initial charge of 20 hot molten slag and copper suffices to ignite the fresh charge.

Firstly, a new charge is introduced which 25 is high in sulphur and iron with the object of producing a low-grade matte quickly. Air is blown into the charge with the result that sulphur is oxidized and a molten matte is produced. If additional heat is necessary it 30 can be supplied by the fuel burners 100. For the blowing operation, the furnace would be tilted back into the position shown in Figure 4 so that the tuyères are covered by the charge. As will be understood, care is taken 35 in charging the furnace to provide a charge of such constituents that a proper slag is formed. Additional ore and other materials for the charge are added from time to time and the blowing continued until the furnace 40 is filled with a low-grade matte and slag. In the present process as soon as the furnace is filled to its capacity with molten slag and matte the furnace is tilted to bring the tuyère above the bath, the air-blast is turned off and 45 a thin layer of preferably pyritic copper ore or other fluxes is spread evenly over the surface of the slag, by means of the pan 61 and directing nozzle 62. The fuel burners are now turned on and the pyrite ore is melted 50 down. The pyrite charge when melted produces a low-grade matte which intermingles with the slag as it passes downwards and by 55 its strong affinity for the copper present in the slag carries the copper with it into the matte below, previously produced. The effect is that the slag is cleaned of copper. This 60 cleaning of the slag in the same furnace chamber after bessemerizing is an important feature of the process to which the invention 65 is adapted as in the usual bessemerizing converter practice it is necessary to transfer the slag to another furnace for cleaning with another charge.

When the slag is cleaned sufficiently, the 65 burners may be turned off and the furnace

is tilted over to a position in which the slag-spout 35 will suffice to discharge the molten slag from above the matte. The slag is skimmed rapidly into slag-cars 45 and the furnace is then tilted back again. A further 70 amount of ore is charged into the furnace, preferably containing a larger proportion of silica than during the first blow to allow for a greater oxidation of iron and a matte 75 higher in copper at the end of the second blow. The furnace is then given a second blowing, and this and charging is continued until the furnace is again filled and ready to be skimmed a second time. The slag is thereafter 80 cleaned and discharged as before, and the operation repeated until the furnace contains a full charge of matte of a higher copper content,—which may finally be brought up to 70 or 80 per cent. After the slag has been 85 skimmed from this matte, or white metal as it is called, the charge is further blown by air to bring it to the condition of blister copper. The copper is tapped near the bottom of the furnace from under the slag, and the 90 slag and a sufficient amount, if necessary, of molten copper, is left in the furnace to commence a fresh cycle of operations.

Referring to the modified apparatus shown 95 in Figures 9 to 11, this comprises a tilting furnace-chamber 120 mounted on rollers 121 and provided with an axial-outlet for furnace-gases 122 connected by a gland 123 to a flue 124, and the flue 124 leads eventually through suitable valves 125 to a pair of regenerators 126, 127. The regenerators are 100 also connected by a cross-header 128 to an air-blast or bustle-pipe 129, by way of a coaxial-gland 130. The bustle-pipe is provided with branch pipes 131 leading to tuyères 132, and with a connection 133 to liquid- or powdered-fuel burners 134. The construction so far described is similar to that 105 illustrated in Figures 1 and 2, but it is to be observed that the flue 124 is not branched and does not contain any waste-heat boilers. On the other hand, it is made of a U-shape 110 in vertical section, as shown in Figure 9, so that slag, matte and other materials carried over in the furnace-gases may be thrown down before entering the regenerators 126.

In the construction illustrated in Figures 1 and 2, the suspended matters carried over in the furnace-gases are intended to be thrown down in the flues 73, 74 and the waste-heat boilers 77, 78. The latter, as will be appreciated, are more easily cleaned of deposited material than are the regenerators and, moreover, as their surfaces are relatively cool they tend to throw down the suspended matters in the form of dust rather than to allow them 115 to accumulate in molten or coagulated masses.

In operating according to the present invention, much less dust is created than in an ordinary reverberatory furnace, because the 120 ore is charged into the furnace in its natural 125 state.

state, which is cold and moist, and is not liable to give rise to the production of dust in anything like the same degree as is the ordinary dry and dusty calcined product of a roasting operation as ordinarily charged into a reverberatory furnace.

Referring to Figure 12, this shows a furnace-chamber 220 provided with tuyères 232 and liquid-fuel burners 234, the furnace being 10 provided with an axial outlet 222 connected through a gland 223 to waste-heat boilers 224. The outgoing gases, however, instead of passing through regenerators for treating the blast are passed into waste heat boilers only. 15 A connection 246, 247 is provided to a chimney-stack, which is not illustrated in the drawings and an alternative flue 240 to an acid recovery plant 245 is indicated diagrammatically in the drawings. The furnace is 20 mounted on rollers, as before. As will be appreciated, in this case the waste heat boilers would be designed to absorb as large a proportion as feasible of the heat carried by the outgoing gases. The outgoing gases, being 25 rich in SO_2 , can be employed for the recovery of this constituent where there is a market for it.

It will be understood that while the description hereinbefore relates specially to copper and the minerals of copper, the apparatus will be equally adapted to the smelting of nickel sulphides, which occur with copper sulphide ores, to 80% matte, and to the smelting of other sulphide ores.

25 The tilting furnace arranged with tuyères on the side, as described, could be used for converting matte only, in place of the ordinary converter. The end discharge and the axial gland for the outgoing gases prevents dilution with the outside air and the heat in the gases or the SO_2 content could be more readily utilized for steam or acid respectively than in the ordinary converter.

I claim:—

1. In combination, a furnace, for the smelting of copper-ores and the like, comprising a reverberatory furnace-chamber having a length considerably in excess of its breadth or height and mounted to tilt about a longitudinal axis, air-preheating apparatus therefor, an axial furnace-outlet for gases connected to the air-preheating apparatus, an axial gland in said outlet to permit tilting of the furnace, tuyères in the furnace near the bottom thereof, and an air-blast pipe extending along the furnace with branches to the tuyères, the air-blast pipe being connected to the air-preheating apparatus.

2. A furnace as claimed in claim 1 provided with a plurality of charging doors along the opposite side thereof from the air-tuyères.

3. The combination with a furnace as claimed in claim 1 of means for introducing an ore-charge, said means comprising an ore-hopper, a charging belt mounted beneath the

hopper, and means to drive it at a speed sufficient to throw the ore into the furnace.

4. The combination with a furnace as claimed in claim 1 of means for introducing an ore-charge, said means comprising an ore-hopper, a charging belt mounted beneath the hopper, means to drive it at a speed sufficient to throw the ore into the furnace, and directing means to spread the driven ore over a wide area within the furnace.

5. A furnace as claimed in claim 1, wherein in the hot blast pipe is connected also to fuel-burners at one end.

In testimony whereof I affix my signature.

ALEXANDER GRANT McGREGOR.
